MACHINE FOR TRIMMING FABRICS

Albert H. Schumacher, Passaic, N. J., assignor, by
mesne assignments, to Reconstruction Finance
Corporation, a corporation of the United States

Application August 31, 1935, Serial No. 38,741

14 Claims. (Cl. 26—16)

This invention relates to machines for trimming fabric and particularly machines provided with a revolving fly blade which is operated in conjunction with a ledger blade for shearing off portions of the nap or pile of the fabric as the fabric is passed over a pattern device thereby producing a design or pattern on the fabric.

The object of the present invention is to improve the pattern-producing mechanism in machines of the indicated type whereby such machines will be enabled to produce a large variety of designs or configurations on fabric.

Other and more specific objects will appear from the following detailed description taken in connection with the accompanying drawings in which Fig. 1 is a fragmentary front view of a trimming machine embodying the invention with several of the elements omitted to show the pattern-producing mechanism more clearly; Fig. 2 is a side elevation of that portion of the machine illustrated in Fig. 1 including the means for feeding the fabric through the machine; Fig. 3 is a fragmentary plan view of a portion of the mechanism shown in Figs. 1 and 2; Fig. 4 is a section taken along the line 4—4 of Fig. 3; Fig. 5 is an enlarged fragmentary detail of a portion of the mechanism shown in Fig. 1; Fig. 6 is a sectional view taken along the line 6—6 of Fig. 5 and including a sectional view of the fly blade; Fig. 7 is a plan view of a piece of fabric that has passed through the machine; Fig. 8 is a fragmentary front view illustrating another form of the pattern device over which the fabric passes; Fig. 9 is a sectional view taken along the line 9—9 of Fig. 8 in which is also indicated the positions of the fly and ledger blades and Fig. 10 is a plan view of a portion of fabric after it has passed through a trimming machine provided with the pattern device illustrated in Figs. 8 and 9.

Referring more particularly to Figs. 1 to 6 of the drawings, the reference character 1 indicates the supporting frame of the trimming machine on which a rest support 2 is mounted for supporting the pattern device or cloth rest of the pattern-producing mechanism over which the fabric A is passed or drawn in the direction indicated in Fig. 2 of the drawings and which is designated generally by the numeral 3. As shown in Fig. 2, the fabric is fed to the cloth rest 3 by passing it under a guide roll 4 which is rotatably mounted upon the front portion of the frame 1 and over a guide roll 5 disposed in parallel relation with the cloth rest. The horizontally journaled shaft 6 which carries the guide roll 5 also carries a pair of temple rings 7 which are posi-

tioned on each side of the roll 5. The temple rings 7 are provided with radially projecting pins which take hold of the fabric as it passes over them and prevent the fabric from moving laterally on the cloth rest 3 so that when the machine is in operation the cutting or shearing elements can operate upon the surface of the fabric with the proper effect. After the fabric has passed over the cloth rest 3 it rides over a card cloth covered roll 8 and then passes to a take-up roll or a finishing machine.

Above the cloth rest 3 is journaled horizontally and parallel to the cloth rest a shaft 9 carrying a rotary fly blade 10 of usual construction. The shaft 9 is rotatably supported in bearings 11 carried by a shear head or frame 12 which also carries a properly adjusted stationary ledger blade 13, such blade being positioned substantially tangentially to the peripheral path of the fly blade 10. The frame 12 is provided with trunnions 14 which are rotatably supported by the frame 1 and about which the frame 12 may be pivoted in a clockwise direction, as viewed in Fig. 2, by depressing the lever 15 pivotally attached to the rear portion of such frame thereby raising the fly blade 10 and ledger blade 13 and enabling the operator of the machine to inspect the cloth or the cloth rest or for any other purpose. Normally however the blade-carrying head of the frame is set to a position to bring the shearing line formed between the fly blade 10 and the ledger blade 13 a slight distance away from the upper portion of the cloth rest 3. The arrangement and construction of the rotary fly blade, ledger blade and the shear head or frame therefore are well known in the art and only such portions thereof as are necessary to an understanding of the present invention are illustrated in the drawings. The rotary fly blade 10 may be driven in any suitable manner, as by means of a belt (not shown) connected with a pulley 16 on the fly blade shaft 9 and with a pulley which is driven by an electric motor through suitable connecting mechanism (not shown).

The cloth rest 3 in one embodiment of the invention, comprises a back plate 20 which seats on a ledge 21 provided on the rest support 2 and against the front face 22 of such support which is inclined rearwardly toward the cutting edge of the ledger blade 13, as is clearly shown in Fig. 6 of the drawings. The back plate 20 is fixedly secured to the rest support 2 by means of screws 23 which extend through openings provided in the lower or base section thereof and are screwed into the front face 22 of the rest support 2. The

upper section of the back plate 20 is reduced in thickness so that a shoulder 24 is formed lengthwise of said plate, such upper section being provided at its working edge with a plurality of teeth 5 25 between which are notches 26. As the cloth passes over the upper edge of the back plate 20 certain portions thereof will be elevated or raised by the teeth 25 while the remaining portions thereof will sag down into the notches 26 due to 10 the tension under which the cloth is placed as it is passing over such plate. The teeth 25 are close to the shearing line formed between the fly blade 10 and the ledger blade 13 so that the raised portions of the cloth passing over such teeth will 15 be reduced in thickness by the blades 10 and 13 while the sagged portions will be untouched thereby by forming sheared lines or grooves in the cloth.

Supported by the back plate 20 is a front plate 27, the upper section of which is substantially 20 thicker than the lower section so that a shoulder 28 is formed lengthwise of said plate on the rear side thereof. The front face of the upper section is inclined away from the plane of the outer surface of the lower section towards the shearing line so that the upper edge of such section is slightly thinner than the upper edge of the back plate 26, as is illustrated in Fig. 6. The upper working edge of the front plate 27 is provided with a plurality of teeth 29 between which are 30 notches 30. In the drawings the teeth and notches of the front plate 27 are shown as being formed exactly like the teeth and notches on the back plate 26. It will be apparent however that the dimensions of the teeth and notches of one 35 plate may be formed entirely different from that of the other plate in order to diversify the designs to be cut in the cloth. The front plate 27 is slidably supported upon the back plate 20 by means of screws 32 which extend through apertures 33 40 provided in the front plate 27 and are threaded into the back plate 20. The screws 32 are provided with washers 34 which function in the nature of guides to prevent outward movement of the front plate 27 during its sliding movement 45 and to keep the teeth 29 in operative relation with the teeth 25 of the back plate 20 and the cutting mechanism. The front plate 27 is provided with a plurality of angularly shaped slots 35 through each of which extends a pin 36, as 50 shown in Figs. 5 and 6. The pins are secured to the back plate 20 in any suitable manner and may extend through suitable perforations in the back plate 20 and be provided with heads which are confined in countersunk recesses on the rear of 55 the back plate 20 by the rest support 2, as shown more clearly in Fig. 6.

It will be seen from the above that the front plate 27 of the cloth rest is mounted for longitudinal movement on the back plate 20 which is 60 fixedly secured to the rest support 2. When the front plate 27 is moved to the right from the position illustrated in Fig. 5, the angularly shaped slots 35 and the pins 36 cause such plate to move downwardly until the pins 36 reach the highest 65 point of the lower edges of the slots 35 or in the slots illustrated, the mid points thereof, thus causing the teeth 29 to be drawn downwardly from the level of the teeth 25, the teeth 29 being positioned directly below the teeth 25 when the 70 pins 36 are positioned at the mid points of the slots 35. As the front plate moves further to the right it is caused to move upwardly by the camming action of the edges of the angular slots 35 on the pins 36 thereby raising such plate and 75 when the pins 36 are positioned in the left ends

of the slots 35, the teeth 29 will be positioned on the right side of the teeth 25 and at the same level. By reason of this arrangement, when the teeth 25 and 29 are positioned as shown in Fig. 5 a path 5 as wide as the width of the adjacently positioned teeth will be sheared in the nap of the cloth by the cutting mechanism. When the front plate 27, however, is moved to the right the teeth 29 will not be able to raise the cloth sufficiently to enable the cutting mechanism to shear the cloth 10 until the front plate 27 reaches the end of its range of movement and the teeth 29 are again on a level with the teeth 25. Thus during this movement of the teeth 29, the sheared paths in the cloth will only be as wide as the width of the 15 teeth 25. When the teeth 29 however are again on a level with the teeth 25 the sheared paths in the cloth will again be as wide as the width of the adjacently positioned teeth 25 and 29, the path sheared in this position of the teeth 29 being to 20 the right of the path sheared by the teeth 25. Due to the time interval involved in moving the plate 27 from left to right, the beginning of the paths produced by the teeth 29 in their new positions start at a point below the ending of the 25 path sheared to the left of the path produced by the teeth 25. By thus moving the front plate 27 back and forth on the back plate 20 a design such as shown in Fig. 7 of the drawings will be produced, the numeral 37 in such figure indicating the nap of the cloth and the numeral 38 indicating the sheared path produced by the teeth 25 and the reciprocating teeth 29. It will be evident that the form of the design may be varied by varying the rate of movement of the front 30 plate 27 or by varying the form of the slots 35. The slots 35 are preferably so formed on the front plate 27 that when the latter is at its lowermost position the shoulder 28 thereof will just engage with the shoulder 24 formed on the back plate 20. The slots 33 should be of sufficient size to enable the front plate 27 to move freely on the back plate 20.

The mechanism for reciprocating the front plate 27 comprises a stub shaft 40 provided on said plate, (see Figs. 3, 5 and 6) and upon which is pivotally supported one end of a bent rod 41. The rod 41 may be maintained in position on the shaft 40 by means of a cotter pin which extends through an opening provided in the outer end of said shaft. The other end of the rod 41 extends through a bearing 42 provided on the adjacent end of a sliding link 43 positioned to one side of the machine. The rod 41 is securely connected to the link by a pair of nuts which are in threaded engagement with a screw thread provided on the rod 41 and are disposed on each side of the bearing 42. It will be observed that by adjusting the nuts on the rod 41 the length of the rod from the bearing 42 to the stub shaft 40 may be varied 60 whereby the range of movement of the front plate 27 is also varied.

The link 43 extends through a pair of spaced guides 44 secured in position upon the top surface of a supporting plate 45 carried by the 65 frame 1 and is provided at its other end with an enlarged rectangularly shaped cam frame 46. An actuating roller 47 carried eccentrically on the outer surface of a disc 48 engages with the inner sides of the cam frame 46 during its rotational movement and reciprocates the latter and therefore the link 43 from right to left, as viewed in the drawings. The disc 48 is integrally formed with a sleeve 49 which is fixedly secured on the end of a shaft 50. The shaft 50 is supported in 70 75

the bearings 51 and 52 carried on the supporting brackets 53 which are secured to the frame of the machine. A driving sprocket 54 is secured to the shaft 50 intermediate the bearings 51 and 52 and is connected to a driving mechanism, not shown, by means of a driving chain. Thus as the sprocket 54 is rotated by the driving mechanism, the disc 48 will be rotated in the same direction, causing the roller 47 to contact successively, first with one side and then the other of the cam 46, thereby causing reciprocating movement of the link 43 and the rod 41. The reciprocating movement of the rod 41 will be imparted to the front plate 27 thereby causing the teeth 28 thereof to be positioned first on one side and then the other of the teeth 25 on the back plate 20, as hereinbefore explained. The range of movement of the link 43 may be varied by varying the position of the roller 47 or the form of the cam frame 46 on the link 43. The range of movement of the link may also be controlled by providing a stop member 55 on the upper side thereof in operative connection with one of the guides 44 so that as the link moves back and forth the stop member 55 will engage with first one side and then the other of the top portion of the guide 44 and limit the movement of the link 43.

In order that the reciprocating movement of the front plate 27 may be made practically instantaneous, I provide additional means for increasing the velocity of the movement of the link 43 in the direction in which it is moved by the cam frame 46 and the roller 47. This means comprises a casing 57 fixedly secured to the supporting plate 45 and positioned at right angles to the path of movement of the link 43. Contained within the casing 57 is a plunger 58 whose range of movement is limited by a pin 59 which is provided on such plunger and which engages with a slot 59' provided in the upper surface of the casing. The plunger 58 is arranged so that it normally tends to move outwardly under the tension of a spring 60 which is positioned between the plunger 58 and a screw member 61 threadedly engaging with the interior surface of the outer end portion of the casing 57. The tension on the spring 60 may be varied by adjusting the position of the screw 61 within the casing 57. Pivotedly supported at 61' within the opposite end of the casing 57 is a lever member 62 whose inner end is in contact with the adjacent end of the plunger 58 and whose outer end is positioned exteriorly of the casing 57 and is provided with a slot 63. The link 43 is provided with a pin 64 which extends through the slot 63.

It will be seen from the above that when the link 43 is starting to move either to the right or the left, as viewed in the drawings, under the influence of the cam frame 46 and the roller 47 that the lever 62 will be rotated in the same direction about its support by means of the pin 64 and the slot 63 thereby causing the inner end of the lever 62 to bear against the plunger 58 and compress the spring 60. When the link 43 has moved sufficiently to cause the inner end of the lever 62 to move past the axis of the plunger 58 the tension on the spring 60 will cause the plunger 58 to snap forwardly thereby causing the lever 62 to snap in the same direction it had been moving and through the slot 63 and pin 64 moving the link 43 almost instantly to the end of its range of movement. By forming the inner end of the lever 62 so that its surface of contact with the plunger 58 is reduced to a minimum as by

making it wedge-shaped so that its contact with the plunger is along a vertical line, (see Figs. 3 and 4), the device is made very sensitive, the plunger 58 under the tension of the spring 60 snapping the lever aside just as soon as its line of contact has passed the axial or dead center of such plunger. The inner end of the lever 62 may also be formed so that its contact with the plunger 58 is a point. Small rollers may also be provided on the inner end of the lever 62 to reduce to a minimum the friction between such lever and the plunger 58.

In Figs. 8 and 9 of the drawings, I have illustrated another embodiment of my invention in which both the front and back plates of the cloth 15 rest are movably mounted on the rest support 67. In this embodiment, the back plate 66 is slidably supported by the sets of screws 68 and 69. The line of screws 68 extend through elongated slots 70 disposed lengthwise of the back plate 66 along 20 the bottom edge portion of its lower section, said screws being in threaded engagement with the rest support 67. The upper line of screws 69 extend through similarly formed slots 71 provided in the upper section of the back plate 66 25 and into the rest support 67. The line of screws 69 also extend through rectangular slots 72 formed in the front plate 73 for slidably supporting the latter in the same manner as the front plate 27 previously discussed. Washers 74 30 are provided on the screws 69 for maintaining the back and front plates in proper position on the rest support so that the teeth thereof will properly cooperate with the cutting mechanism. The screws 68 and 69 may be provided with 35 loosely mounted sleeve members so that the front and back plates may reciprocate on such screws with a minimum of friction. The front face of the rest support 67 may be hollowed out, as shown in Fig. 9, to reduce the friction between 40 the front face thereof and the back plate 66 during the latter's movement. In order to give the front plate 73 a movement similar to that of the front plate 27, previously discussed, a plurality of pins 75 are provided which are secured at 45 their inner ends to the rest support 67 and extend out through slots 76 and 77 provided in the back and front plates, respectively. The slots 76 of the back plate are similar to the slots 70 and 71, so that no transverse movement is imparted to 50 the back plate 66. The slots 77 of the front plate 73 however are angularly formed so that as the front plate 73 is reciprocated back and forth, it is given a motion similar to that described with respect to the front plate 27 thereby moving the 55 teeth of such plate away from the cutting line and changing their position with respect to the teeth on the back plate 66. The front and back plates are each provided with a rod 78 which is secured to an actuating mechanism such as was 60 above described with respect to the modification in Figs. 1 and 6, said mechanisms being adapted to move the plates in opposite directions during their longitudinal movement. The actuating mechanisms for the plates may be disposed 65 on opposite sides of the machine, as is indicated in Fig. 8, or they may be positioned together on one side of the machine. In the latter case they may both be associated with the shaft 50 and sprocket 54.

It will be seen from the above that when the parts of this embodiment of the invention are in the position indicated in Fig. 8 that the row of paths 79 are being sheared in the nap of the fabric as shown in Fig. 10, such paths being equal 75

in width to the combined width of the adjacently disposed teeth of the front and back plates 73 and 66, respectively. On the next operation of the driving mechanisms of the plates, the back plate 66 is slidably moved to the left, as viewed in Fig. 8, causing the shearing mechanism to cut a transverse path in the nap of the material which is approximately equal to the thickness of the teeth on the back plate. At the same time 10 the front plate 73 which is carried on the back plate 66 will be moved to the right and simultaneously lowered by reason of the camming action of the edges of the slots 77 on the pins 75 thereby lowering the teeth of the front plate 15 from the cutting line and moving them over to the opposite sides of the teeth on the back plate 66. The pins 75 and slots 77 will then raise the front plate 73 on continued movement of the latter until the teeth on such plate are disposed 20 adjacently to the right sides of the teeth of the back plate and in line therewith so that each pair of teeth on the front and back plates are again feeding the cloth to the cutting mechanism, this time producing the row of paths 80. It will thus 25 be seen that the operation of the mechanism will produce a series of alternately aligned rectangles on the surface of the cloth thus imparting to the surface of the material a figure or pattern of the peculiar nature indicated in Fig. 10 consisting 30 of two series or rows of alternately spaced rectangles extending longitudinally of the fabric.

It will be observed that by providing a cloth rest composed of a plurality of plates which have longitudinal and/or transverse movement with 35 relation to each other, I am enabled to accomplish the desirable object of supplying a cloth finishing machine which is capable of producing an endless number of designs or figures on fabric material, can be readily adjusted to change the 40 design to be produced and is relatively simple and sturdy in construction.

While I have shown and described two specific forms of my invention, it is apparent that numerous modifications may be made in the 45 mechanisms without departing from the scope of the invention as covered by the appended claims whose purpose it is to include and embrace such modifications or equivalents.

I claim:

50 1. In a pattern shearing machine, the combination of a shearing device, a fabric-supporting rest associated with said shearing device and adapted to hold portions of a fabric surface in position to be cut by said shearing device, said rest comprising a plurality of pattern elements arranged for movement relative to each other and mechanism for causing relative movement of said elements.

55 2. In a pattern shearing machine, the combination of a shearing device, a fabric-supporting rest associated with said shearing device and adapted to hold portions of a fabric surface in position to be cut by said shearing device, said rest comprising a plurality of pattern plates 50 adapted to support the fabric and arranged for movement relative to each other and mechanism for reciprocating at least one of said plates.

60 3. In a pattern shearing machine, the combination of a shearing device, a fabric-supporting rest associated with said shearing device and adapted to hold portions of a fabric surface in position to be cut by said shearing device, said rest comprising a support, a pattern element mounted on said support, a second pattern element 65 mounted adjacently to said first pattern

element and in sliding engagement therewith, and mechanism for reciprocating at least one of said pattern elements.

4. In a pattern shearing machine, the combination of a shearing device, a fabric-supporting rest associated with said shearing device, said rest comprising a plurality of pattern elements, mechanism for reciprocating at least one of said pattern elements along its longitudinal axis and means for causing a relative movement of said 10 elements transversely of their longitudinal axes. 5

5. In a pattern shearing machine, the combination of a shearing device, a fabric-supporting rest associated with said shearing device, said rest comprising a support, a pattern plate mounted 15 on said support and adapted to support the fabric at all times, a second pattern plate mounted adjacently to said first pattern plate, mechanism for causing a relative movement of said pattern plates and means for causing said second 20 plate to move into and out of operative association with said shearing device during such relative movement.

6. In a pattern shearing machine, the combination of a shearing device, a fabric-supporting 25 rest associated with said shearing device, said rest comprising a support, a pattern plate mounted on said support and adapted to support the fabric, a second pattern plate support adjacently to said first pattern plate, mechanism for reciprocating 30 said second pattern plate, means for maintaining said plates in slidable contact during such reciprocating movement and means for causing said second plate to move into and out of operative association with said shearing device during 35 said reciprocating movement.

7. In a pattern shearing machine, the combination of a shearing device, a fabric-supporting rest associated with said shearing device, said rest comprising a support, means fixedly securing 40 a pattern plate to said support, a second pattern plate, means supporting said second pattern plate in slidable contact with said first pattern plate, mechanism for reciprocating said second pattern plate along its longitudinal axis, and camming 45 means for causing said second plate to move into and out of operative association with said shearing device during its reciprocating movement. 50

8. In a pattern shearing machine, the combination of a shearing device, a fabric-supporting 55 rest associated with said shearing device, said rest comprising a support, a plurality of pattern plates mounted on said support, means for maintaining at least one of said pattern plates in operative association with said shearing device at all times, means for intermittently moving the other of said pattern plates into and out of operative association with said shearing device, and means for causing a reciprocating movement between said pattern plates in the direction of the shearing 60 line. 65

9. In a pattern shearing machine, the combination of a shearing device, a fabric-supporting rest associated with said shearing device, said rest comprising a plurality of notched plates arranged 70 adjacently to each other and adapted to support the fabric, mechanism for causing a reciprocating movement of said notched plates relative to each other, means for maintaining at least one 75 of said notched plates in operative association with said shearing device at all times, means for causing the other of said notched plates to move into and out of operative relation with said shearing device during said reciprocating movement 75.

and means for maintaining the plates in slidable contact with each other.

- 5 10. In a pattern shearing machine, the combination of a shearing device, a fabric-supporting rest associated with said shearing device and adapted to hold portions of a fabric surface in position to be cut by said shearing device, said rest comprising a plurality of pattern plates arranged adjacently to each other and adapted to support the fabric, mechanism for reciprocating one of said plates along its shearing line and mechanism for reciprocating the other of said plates relative to said first mentioned plate and in an opposite direction.
- 15 11. In a pattern shearing machine, the combination of a shearing device, a fabric-supporting rest associated with said shearing device, said rest comprising a plurality of pattern plates arranged adjacently to each other and adapted to support the fabric, mechanism for reciprocating one of said plates along its shearing line, mechanism for reciprocating the other of said plates relative to said first mentioned plate and in an opposite direction and means for causing said second plate to move into and out of operative association with said shearing device during its reciprocating movement.
- 20 12. In a pattern shearing machine, the combination of a shearing device, a fabric-supporting rest associated with said shearing device and adapted to hold portions of a fabric surface in

position to be cut by said shearing device, said rest comprising a plurality of pattern elements arranged for movement relative to each other, mechanism for causing relative movement of said elements and means for causing said mechanism to move with a snap action.

10 13. In a pattern shearing machine, the combination of a shearing device, a fabric-supporting rest associated with said shearing device, said rest comprising a plurality of pattern plates arranged adjacently to each other and adapted to support the fabric, mechanism for causing a reciprocating movement of said pattern plates relative to each other, means for causing said reciprocating mechanism to move with a snap action, 15 and means for moving at least one of said plates into and out of operative relation with said shearing device during said reciprocating movement.

14. In a pattern shearing machine, the combination of a shearing device, a fabric-supporting rest associated with said shearing device, said rest comprising a plurality of pattern plates arranged adjacently to each other and adapted to support the fabric, mechanism for causing a reciprocating movement of said plates relative to each other, means for moving at least one of said plates into and out of operative relation with said shearing device during said reciprocating movement and stop means adapted to limit the movement of 25 said plates relative to each other. 30

ALBERT H. SCHUMACHER.
